(57) **CLAIM**

The ornamental design for a neurostimulator electrical connector as shown and described.

DESCRIPTION

FIG. 1 is a perspective view of a neurostimulator electrical connector showing our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings are for the purpose of illustrating portions of the neurostimulator electrical connector, which form no part of the claimed design.
